UNITED STATES PATENT OFFICE.

EDWARD W. HAKE, OF CINCINNATI, OHIO.

HEATING-STOVE.

1,099,359.

Specification of Letters Patent.

Patented June 9, 1914.

Application filed December 13, 1911. Serial No. 665,479.

To all whom it may concern:

Be it known that I, EDWARD W. HAKE, a citizen of the United States, residing at Cincinnati, in the county of Hamilton and State 5 of Ohio, have invented certain new and useful Improvements in Heating-Stoves, of which the following is a specification.

It is the object of my invention to provide a heating stove with novel means for increasing the heat-radiating surfaces; further to provide a heating stove with novel means for causing circulation of air thereabout and therethrough; further to provide a novel arrangement of heat-radiating flues; 15 and the invention will be further readily understood from the following description and claims, and from the drawings, in which latter:

Figure 1 is a central vertical cross-section 20 of my improved device, taken on a line corresponding to the line 1—1 of Fig. 2, and showing the dome partly in side elevation. Fig. 2 is a central vertical cross-section of the same, taken on a line corresponding to the line 2—2 of Fig. 1. Fig. 3 is a rear elevation of my improved device with the upper part of the stove broken away and the rear plate which forms the rear wall of the rear flue removed. Fig. 4 is a horizontal 25 cross-section of my improved device, taken on a line corresponding to the line 4—4 of Fig. 3. Fig. 5 is a horizontal cross-section of my improved device, taken on a line corresponding to the irregular line 5—5 of Fig. 1. Fig. 6 is a vertical cross-section, taken on a line corresponding to the irregular line 6—6 of Fig. 1. Fig. 7 is a side elevation of the lower portion of the stove partly broken away; and, Fig. 8 is a sectional detail on the line 8—8 of Fig. 3.

11 represents the fire-pot, 12 the grate, 45 13 the ash-pit, 14 the fuel-reservoir, which may be closed at its top by a lid 15 and have thereabove a dome 16. These parts may be of any ordinary or usual construction.

17, 18 are partition-plates, shown at the front and rear of the stove, connecting the top of the fire-pot and top of the ash-pit, and located respectively in front and rear 50 of the fire-pot, and, with the ash-pit, forming a heat-radiating wall about the fire-pot. At their side edges these partition-plates connect, respectively at the front and rear of the stove, with the side walls 19, 20 of 55 the stove, doors 21, 22 being located in said

respective side walls between said partition-plates.

23 is the ash-pit door, the wall 24 of the ash-pit in which said door is located, being the only wall of said ash-pit in the present 60 exemplification of my invention exposed at the outside of the stove. The other walls of said ash-pit including its bottom wall, and said partition-plates, form the inner wall or body of the lower portion of the stove. 65

There are a series of flues 25, the upper ends of which have communication with the firing means, exemplified as the fire-pot. There are openings 26 between adjacent flues, and there is an air-space 27 behind the 70 inner walls of said flues, with which said openings communicate, this air-space being shown between said flues and the partition-plate 17 and ash-pit 13. These flues are shown at the front of the stove and extend 75 up and down and curve outwardly lengthwise of the flues, (see Fig. 1), and are arranged cross-sectionally in an arc across the front of the stove, (see Figs. 4 and 5). There is a further series of flues 28 extending crosswise of the bottom of the stove, preferably from front to rear. The flues 28 have openings 29 between them, and there is an air-space 30 between said flues and the bottom wall of the ash-pit of the stove, this 80 air-space communicating with the openings 29. There is a cross-channel 31 between the adjacent ends of the flues 25 and 28, for forming communication between said two series of flues, and permitting the products 85 of combustion in the fire-pot to pass from the fire-pot through the series of flues 25, across the cross-channel 31, and into and through the series of bottom flues 28, from the rear ends of which latter the products of 90 combustion are discharged into a rear flue 32, which extends across the back of the stove, and the outer wall of which is formed by the removable rear wall 33 of the stove, in which latter a pipe-connection 34 may 100 also be located, this pipe-connection arranged to be connected with a suitable chimney. There is a clean-out door 35 in the wall of said cross-channel. The bottom air-space 30 connects with the air-space 27, between the wall of the ash-pit and the inner upper corner wall 36 of the cross-channel 31, as shown at 37.

40 is an air-passage located between the inner wall 41 of the rear flue 32 and the par- 110

tition-plate 18 and ash-pit 13, and communicates at 42 with the air-space 30.

Referring to Fig. 1, it will be noted that the front, bottom and rear flues form a substantially U-shaped passage for the products of combustion, the upper end of one limb of which communicates with the firing means, and the other limb of which has suitable connection with the chimney adapted to receive the products of combustion. It will be further noted that there is a substantially U-shaped heat-radiation space between said flues and the inner stove-body, one limb of which communicates with the air-openings between the front flues, and the other limb of which forms the up-draft heated-air conduit, which is shown extending to substantially the top of the stove at its rear, for drawing the currents of heated air through said heat-radiation space, said currents of heated air being replenished from the cooler air at the front and sides and under the bottom of the stove. The outer wall 44 of the stove, laterally of the ash-pit, preferably at the left side of the stove, is provided with air-openings 45, which communicate with an air-space 46 between said outer wall and the wall of the ash-pit, the said air-space 46 communicating at its bottom with the air-space 30. The air-space 46 is preferably separated from the air-passage 40 at the side of said air-space by a wall 48, the air-passage 40 connecting with the air-space 46 at the bottoms of said air-passage and air-space, for drawing the currents of air through said air-space and air-passage, the said air-passage extending upwardly a substantially greater distance than said air-space and being heated throughout a large portion of the same at both its front and rear walls, whereby the lighter heated air-currents thus established through the air-passage 40 draw the cooler and heavier air at the side of the stove through said air-openings 45 and air-space 46 into and through said air-passage 40. The air-passage 40 preferably continues above the horizontal plane of the fire-pot through the upper part of the stove, the outer wall 50 of said passage being provided adjacent its upper end with openings 51, the upper end of the same being provided with a collar 52 for receiving a suitable pipe or lid. 53 is a damper which is shiftable for opening or closing the passage of the hot-air through said collar. 54 is a usual direct draft damper for opening or closing the direct draft flue 55, and 56 is the usual check-damper for opening or closing direct passage through a usual flue connecting the ash-pit and rear flue. These latter dampers are of usual construction and not more particularly shown, because well known.

In my improved device, the course of the products of combustion is from the fire-pot

down through the upright flues 25, shown located at the front of the stove, and through the bottom flues 28, and thence up the flue 32. This arrangement of flues has the advantage that the products of combustion, while their heat is the greatest, pass through and impart the greatest heat to the upright flues 25 shown at the front of the stove. These flues 25 are exposed at the outside of the stove and as they receive the first contact by the hot products of combustion, they radiate the greatest amount of heat, projecting the same directly into the room. The products of combustion, continuing their course, also heat the lower flues, and the upright and lower flues being heated and spaced from the inner wall of the stove, they radiate heat at all sides thereof. The spacing of these flues from the inside wall of the lower part of the stove also provides passages through which the heated air flows. The course of the air-currents is normally through the bottom openings and the space between the bottom flues and the inside wall-construction of the stove, the greater volume of the heated air-currents passing through the hot air flue 40, which is heated at both its front and rear walls, which thereby creates a suction which will normally draw the air through the bottom of the front openings, the lower air openings, and also normally draw the air through the side air-intake 45 and the side-space 46, and under the bottom of the rear partition of said side-space and through the bottom air space, and thence through said hot air flue 40. The heated air in the upper part of the front space 27 will pass through the upper portions of the front openings and draw its supply selectively from the lower portions of said front openings and the front portions of the bottom openings, depending on the relation of the heat generated by the stove to the heat of the atmosphere surrounding the stove. The heat radiated from the partition-plate 17 will also be projected outwardly into the room.

If the stove is located in a room, the course of the main heated air-currents will be upwardly through the main passage 40. The heated air-currents, when they strike the ceiling, will be deflected toward the wall of the room and pass downwardly along the wall and across the floor, and be redirected through the bottom openings of the stove. It has been ascertained that ordinarily the coldest strata of air is located a slight distance above the floor, approximately nine to eighteen inches above the floor. At approximately the elevation of the coldest strata of air, I provide the air-intake 45, for normally drawing said cold air inwardly about the lower inner body of the stove and discharging the same in heated condition. The heat imparted by the flues, owing to the loca-

tions of said flues and the openings and 5 passages provided for the air, will cause the heated air to pass selectively through said passages and said openings for diffusing the heat in a superior manner.

My improved construction presents a maximum radiating surface, against which the air-currents may impinge, and from 10 which the said air-currents may receive radiated heat for utilizing the heat units of the fuel to best advantage.

My improved device utilizes the flues as means for radiating the heat directly into the room, and also as means for heating air-currents which pass between said flues and the lower inner body of the stove and are discharged in heated condition into the room. In my improved device further, the 15 heat radiated from the bottom of the bottom flues is directed against a cooler strata 20 of air under said flues passing toward the openings between said flues, whereby excessive heat radiation directed against the floor on which the stove is located is avoided, and the downwardly projected heat diffused and 25 projected laterally and also through the openings between said flues.

In my improved device the flues for the products of combustion radiate heat at all 30 sides thereof against air-currents diffused in the room being heated as heated air-currents.

Having thus fully described my invention, 35 what I claim as new and desire to secure by Letters Patent, is:

1. A heating stove of the character described comprising a fire-pot, a heat-radiating wall thereabout, a series of down-draft flues, said down-draft flues communicating 40 with said fire-pot at their upper ends, said down-draft flues spaced from said heat-radiating wall and from one another for forming air-passages between said down-draft flues and between said series of down-draft 45 flues and said heat-radiating wall, and an up-draft flue having connection with said down-draft flues and extending substantially from side to side of said fire-pot, and spaced from said heat-radiating wall for 50 forming an up-draft heated-air space between said up-draft flue and said heat-radiating wall which has connection with said first-named air-passages, and an up-draft heated-air flue which extends upwardly sub- 55 stantially higher than said air-passages and the lower portion of which is formed by said up-draft heated-air space.

2. A heating stove of the character described comprising a fire-pot, a heat radiating wall thereabout including a pit below 60 said fire-pot, a series of down-draft flues, said down-draft flues communicating with said fire-pot at their upper ends, a series

of bottom flues communicating at their forward ends with said series of down-draft flues, said down-draft flues and said bottom flues respectively spaced from one another and from said heat-radiating wall for forming air-passages, and an up-draft flue having 65 connection with the rear ends of said bottom flues and extending substantially from side to side of said fire-pot and spaced from said heat-radiating wall for forming an up-draft heated-air space between said up-draft flue and said heat-radiating wall 70 which has connection with said first-named air-passages, the top of said stove being higher than said passages and flues, and an up-draft heated-air flue the lower portion 75 of which is formed by said up-draft heated-air space, and said up-draft heated-air flue extending to substantially said top of said stove.

3. A heating stove of the character described comprising an inner stove-body 85 which includes a fire-pot, a pit below said fire-pot and partition plates at front and rear of said fire-pot connecting with said pit for forming a heat-radiating wall about said fire-pot, and an outer stove-body extending above said inner stove-body and comprising a series of down-draft flues at the front of said inner stove-body, said down-draft flues connecting with said fire-pot at their upper ends, a series of bottom 90 flues under said inner stove-body connecting at their forward ends with said series of down-draft flues, said down-draft flues and said bottom flues respectively spaced from one another and from said heat-radiating 95 wall for forming air-passages, a side-plate spaced from said inner stove-body for forming an air-passage and provided with air-openings communicating with said last-named air-passage, and an up-draft flue having 100 connection with the rear ends of said bottom flues and extending substantially from side to side of said fire-pot and spaced from said heat-radiating wall for forming an up-draft heated air-passage between said up-draft flue and said heat-radiating wall 105 which has connection at its bottom with said first-named air-passages and said second-named air-passage, and an up-draft heated air-flue the lower portion of which is formed 110 by said last-named up-draft heated air-passage, and said up-draft heated air-flue extending substantially to the top of said outer stove-body.

In testimony whereof, I have signed my 115 name hereto in the presence of two subscribing witnesses.

EDWARD W. HAKE.

Witnesses:

EDWARD SOUTHWORTH,
THERESA SILBER.
